UNITED STATES PATENT OFFICE

2,241,934

FISH ELEVATOR

William F. Schlothan, Ketchikan, Territory of
Alaska

Application October 13, 1939, Serial No. 299,292

3 Claims. (Cl. 198—206)

This invention relates to improvements in elevators, and has reference more particularly to elevators of the continuous belt, bucket type, especially designed for the unloading of the freshly caught fish from the hold of a fishing boat; it being the principal object of the invention to provide a vertical lift elevator whereby the fish may be scooped up, lifted and delivered from a boat without the usual sliding contact with chutes or troughs during the lifting operation, and wherein buckets of special design provide for a greater capacity than is possible by the usual types of elevators now in general use.

It is also an object of this invention to provide an elevator in the form of a portable unit, adapted to be readily placed in or removed from a boat, as required, and which is equipped with its own power unit that adapts it for transfer from boat to boat if which should be desired.

Still further objects of the invention reside in the details of construction of parts of the device, in their combination and mode of operation as will hereinafter be fully described.

In accomplishing the above and other objects of the invention, I have provided the improved details of construction, the preferred form of which is illustrated in the accompanying drawings, wherein—

Fig. 1 is a side view of an elevator embodied by the present invention, parts being in section for purpose of better illustration.

Fig. 2 is another side view of the elevator, showing the removable cover boards used at that side.

Fig. 3 is a cross section, taken on the line 3—3 in Fig. 2.

Fig. 4 is a side view of one of the buckets and a part of the conveyor chain.

Referring more in detail to the drawings: 1 designates a part of a fishing boat of the usual type, having a hold 2 for reception of the fish, and equipped with a sump 3 into which contents of the boat may be drained for removal. The deck of the boat is designated at 4 and this is provided with a hatch 5, through which the present elevator mechanism, designated in its entirety by reference character 6, is applied for use.

The present elevator mechanism comprises a frame structure of rectangular form in cross section, as noted best in Fig. 3, and of a substantial, vertical height so that when disposed in a boat for use with its lower end portion disposed in the sump, its upper end position will be substantially above the deck of the boat, as

understood by reference to Fig. 1. The frame structure comprises the four vertical, corner posts 10 that extend substantially the full length of the elevator frame, and to which sheet metal side plates 11 are fixed, on three sides of the frame, to form an enclosed, vertical shaft. The plates 11 extend somewhat above the hatch and serve to retain the fish that may fill the hold, against sliding into the shaft. On its fourth side, the frame structure is closed by a succession of cover boards 12, disposed edge to edge and one above the other, across the space between corner posts 10 and are adapted to be retained at their ends in vertical guideways 13—13 that are formed by angle iron bars 14 fixed to the corner posts at that side as disclosed in Fig. 3. The wall formed by the succession of boards 12 may extend to a height equal to the plates 11, and it serves to retain the fish from entering the elevator shaft at that side, except as desired, and as provided for by removal of the boards.

At the upper end of the main, or vertical, frame structure formed by the posts 10 and wall plates 11, is a laterally extending frame structure 15 comprising co-extensive horizontal beams 16 and 17 connected at their outer ends by vertical bars 18. Overlying the top end of the frame structure is a cover plate 19.

Extending from the lower end of the frame structure, at opposite sides, are semi-circular plates 20, which rest against the bottom of the sump, and mounted across the lower end of the elevator frame structure is a cross shaft 25, revolvably mounted at its ends in bearings 26 fixed on cross bars 27 that join the lower end of the vertical beams 10. At the upper end of the elevator shaft or elevator frame, is a cross shaft 28 mounted revolvably at its ends in bearings 29 that are fixed on the frame beams or bars 17. Also, parallel with the shaft 28 and mounted by bearings 30 fixed to the bars 17 at the outer end portion of the lateral frame structure 15 is a shaft 32. As will be noted best in Fig. 2, mounted on the various shafts 25, 28 and 32, near the opposite side walls of the frame structure, and in parallel, vertical planes, are paired sprocket wheels 35—35' over which a pair of continuous conveyor chain belts 36 and 36' are mounted for travel; it being noted that the belts have portions adapted to move upwardly within one side of the elevator shaft, then to pass horizontally over the sprocket wheel on shafts 28 and 32, then back and over a set of smaller sprocket wheels 40 on a cross shaft 41, and then directly

downward to the lower end of the shaft and about the sprocket wheels at its lower end. Shaft 41, as seen in Fig. 1, is mounted in bearings 42 fixed to corner posts 10 near the upper end of the frame.

Mounted between the sprocket chains, at regularly spaced intervals are buckets 45. These are fixed solidly to the chain by two adjacent pivots 46-46' as noted in Fig. 4 and therefore retain their position relative to the chain and its direction of travel.

It will readily be understood that, with the belts moving in the direction indicated by the arrows in Fig. 1, the buckets will necessarily move downwardly along one side of the elevator shaft to its lower end, then will travel upwardly.

By removal of boards 12 from the side of the shaft down to a certain level the fish may be admitted from the ship's hold over the top edge of the remaining wall section and will be scooped up with the water and elevated, and delivered from the boat.

As the buckets pass over the sprockets carried by the cross shaft 32, the fish will be dumped therefrom, and to facilitate the discharge from the boat to a receiving vessel, I have provided a chute or trough 50, which rests at its outer end portion on the boat rail and at its inner end has side studs 51 seated removably in upwardly opening notches 52 in the end portions of angle bars 60 that are fixed to the elevator in position to hold the trough directly below the point of discharge from the buckets.

In order that no fish will be lost from the buckets while they are moving horizontally, I have provided a horizontal trough 61 between the cross shafts 28 and 32 and along which the buckets travel just prior to dumping the fish into the delivery chute 50.

For the purpose of driving the elevator chains, I have mounted an electric motor 70 on the upper end plate of the frame structure and have connected this, through a reduction gear mechanism 71, with a cross shaft 72 mounting a sprocket wheel 73 and a wheel 76 on the outer end of cross shaft 32.

In use, for unloading a boat's hold, containing freshly caught fish, the elevator frame is lowered into the hold until its lower end rests in the sump, as shown. Then the side boards 12 are removed, from the top down to just below the fish level and the fish are permitted to flow into the shaft to be scooped up by the upwardly traveling buckets. As the level of fish in the boat goes down, the cover boards 12 are removed accordingly. The buckets, as here used, remove water from the hold along with the fish, and the usual task of taking this out later is avoided.

Such elevators are easily handled, and may be moved from boat to boat, and thus much labor and time saved. Changes in size and structural features might readily be made without departing from the spirit of the invention.

Having thus described my invention, what I claim as new therein and desire to secure by Letters Patent is:

1. An elevator of the character described comprising a frame structure forming a vertical shaft adapted to be disposed through the hatchway of a boat, to extend to the bottom of a hold containing a fluid cargo and to project above the deck, a continuous conveyor belt, with buckets fixed thereto, operable vertically in the shaft, for removal of cargo from the hold and for lateral delivery thereof from the upper end of the shaft, power mechanism mounted on the upper end of the structure for driving the conveyor belt; said shaft being permanently closed about all sides except the side facing the up-going run of the belt and provided at that side with a closing wall comprising sections that are successively demountable from the upper end of the wall downwardly to provide for the inflow of cargo to the shaft over the top edge of that wall in accordance with the removal of the sections.

2. A fish elevator of the character described comprising a frame structure adapted to be extended vertically through the hatchway of a boat to rest on the bottom of the hold and to extend above the boat's deck; said shaft being closed at its lower end and side to a height above level to which the boat is filled with fish; an elevator operable in the shaft for elevation of fish and for their delivery laterally from the upper end of the shaft; said frame being formed along one side with parallel guideways, and a succession of side boards forming the side wall at that side of the frame, with opposite ends retained in the guideways; said boards being successively removable from the guideways to lower the effective height of the wall for inflow of fish to the conveyor.

3. In combination, a boat having a fish cargo hold formed with a drainage sump and a hatchway opening through the deck to said hold, a fish elevator comprising a portable frame structure positioned through the hatchway and resting at its lower end in the sump and extending substantially above the hatchway and having a lateral extension at its upper end, an endless belt conveyor with buckets attached, operable lengthwise of the frame and in the lateral extension for the elevation of fish from the hold and a lateral delivery from the frame; said frame being closed at its lower end and sides to a height above the loading level, and having the side adjacent the upgoing side of the belt closed by side boards that are successively removable to lower the height of the wall for admission of fish to the conveyor, and a delivery trough attached to the upper end portion of the frame for reception and discharge of the fish as received from the conveyor.

WILLIAM F. SCHLOTHAN.
